SPLICE FOR POLES FOR SCAFFOLDING

Filed Feb. 27, 1928

UNITED STATES PATENT OFFICE

FRANK G. KINGSTON, OF WEST SOMERVILLE, MASSACHUSETTS, ASSIGNOR TO BUILDERS' PATENT SCAFFOLDING COMPANY, OF WEST SOMERVILLE, MASSACHUSETTS, A PARTNERSHIP COMPOSED OF FRANK G. KINGSTON, A. R. KINGSTON, C. C. PIMM, AND MABEL G. KITCHEN

SPLICE FOR POLES FOR SCAFFOLDING

Application filed February 27, 1928. Serial No. 257,518.

In the erection of scaffolding or staging for support of workmen engaged in the construction of walls of buildings, and other structures, vertical poles or posts are used which 5 of necessity are of lengths that have to be placed end to end to reach to the desired height. The joining or splicing of adjacent end portions is a matter of vital importance for the stability and safety of the scaffolding. 10 It is also of great practical importance to be able to reduce cost and labor and time in the erection of and taking down the scaffolding to the minimum and yet without any sacrifice of stability and strength. In making my 15 invention I have had all these considerations in mind and in the light of extended practical experience in the building art, and the object of my invention has been to provide pole splice means that will achieve to the utmost 20 the requirements named.

My invention consists in whatever is described by or is included within the terms or scope of the appended claims.

In the drawings I illustrate several embodiments of my invention both for the purpose of disclosing various constructions that may be employed and to illustrate the scope of my invention in its broadest aspect.

In the drawings:

30 Fig. 1 is a perspective view of a splice having a construction that achieves the object of my invention in what I now consider its best form;

Fig. 2 is a horizontal section thereof;

35 Fig. 3 is a side elevation of another embodiment of my invention;

Figs. 4 and 5 are respectively, detail views in perspective of other constructions that may be followed;

40 Fig. 6 is a detail view in perspective of a different construction of splice.

Fig. 7 is a detail view in section showing the swiveled connection between the screw and the plate or shoe of the device shown in 45 Fig. 6;

Figs. 8 and 9 are, respectively, horizontal sections through the splices shown in Figs. 4 and 5.

First describing briefly what is shown in the 50 drawings, Figs. 1-5 it will be found that my

invention is achieved in a structure that comprises opposite and preferably similar or substantially similar pole engaging shoes each of channel shape in cross section and two similar clamps spaced apart vertically, each comprising what may be termed a nut member which is connected with one of the shoes and which has a horizontal threaded hole through it and a screw of crank-form engaging the threaded hole in the nut and adapted to impinge or bear at its inner end against the outer side of the other shoe and thus force the two shoes towards one another and against the opposite sides of the pole ends inserted between the shoes, and all of the members of the splice are permanently assembled so that there are no loose detachable parts apt to become lost or misplaced and requiring special care on the part of the workmen, these considerations being of importance for several 70 reasons. One is that no skilled labor is required for the application and removal of the splices. Another is the minimum of time is required for the application and removal of the splice. Yet another reason is that the 75 staging or scaffolding is transported or moved from building to building and even from town to town so that the likelihood of loss or misplacement of loose detachable parts is very great.

It will be found that my clamp requires the use of no nails or similar attaching means and no special form of abutting ends of the poles.

Describing in detail what is shown in Figs. 1 and 2, there are two similar, straight shoes, 10, each of channel-shape in cross section readily made of sheet metal of sufficient gauge to give requisite strength, which near their ends are permanently joined but slidably joined so that they may be moved towards and from one another for clamping and unclamping purposes and yet never completely separated, they being thus joined by a substantially U-shape strap 11, which is suitably secured to one of the shoes, and the legs of which pass through vertical slots, 12, respectively, in a rectangular metal plate, 13, fastened to the outer side of the other shoe and connecting the ends of said legs out- 100

side of said plate is a metal horizontal bar, 14, which at its transverse center has a horizontal screw threaded hole, 15, and a cranked clamp screw, 16, whose inner end is adapted to bear against the outer side of said plate, 13. The ends of said bar, 14, enter slots in said legs and are upset or riveted upon the outside.

The manner of using the clamp shown in Figs. 1 and 2 is very simple. The shoes are slipped over the upper end portion of a standing pole about half way and by the action of the screw of the lower clamp, it is held in place and then the lower end of the next pole is inserted between the shoes until it rests upon the top of the lower pole and then all is made secure by the screw clamps. The contiguous ends of the clamped poles need have no special configuration whatever and as they are rigidly and firmly held by the clamps there is no necessity for using nails.

Referring to the embodiment of my invention shown in Fig. 3, it is similar in all respects to what is shown in Figs. 1 and 2, excepting one of the shoes is made in two sections, by what in effect is a horizontal division so that the lower clamp is attached to a lower section, 16, and the upper clamp to an upper shoe section, 17, the two sections overlapping one another. By this sectional construction enough flexibility or adaptability is given the clamp so that in the event that adjoining portions of poles are of different size or area in cross section the splice may conform thereto and the job of inserting the lower end of an upper pole may be facilitated by swinging outward the upper section so as to increase the size of the space between the shoes. Preferably in order to make up or compensate for the weakening effect of making the shoe in sections, a bolt or bolts, 18, are provided to connect the sections where they overlap so that while loosened up for assembly purposes the two sections may be rigidly tied or held together where they overlap after the poles and clamps are assembled or put together and thus the splice given requisite strength to resist lateral strains.

While the strap, 11, and the plate, 13, may be riveted to the respective shoes yet I prefer as being a less expensive construction to attach them to their respective shoes by a pair of upper and lower tongues, 19, struck or punched out of the metal of the shoe and folded or bent down over the adjacent edge of the strap or plate. Preferably in the case of the plate, each tongue is folded into a notch, 20, in the edge of the plate to add to the rigidity of the connection.

In each of Figs. 4 and 5 embodiments of my invention are illustrated by which the connection between opposite shoes is obtained without the employment of separate

straps, but as shown in Fig. 4 one shoe is provided with integral legs, 21, that project from opposite edges of the side flanges which pass through vertical slots 22, in the companion shoe and the clamp screw, 16, passes through a threaded hole in a bar, 23, similar to that shown in Fig. 1 and similarly secured to the legs. As shown in Fig. 5, the member, 24, with the threaded hole for the clamp screw, may be integral with one of the legs, 25, and to provide sufficient thickness when the gauge of the metal is inadequate, the nut member may be formed by folded or doubled over portions, or a nut may be placed between the overlaps which would be less expensive than tapping the holes in the overlaps.

In each case shown in Figs. 4, 5, 8 and 9 the screw-engaged shoe is shown in dotted lines in Figs. 4 and 5 and in full lines in Figs. 8 and 9, and its web is slotted to pass over the legs, 21, and 25, as the case may be, as shown, and such shoe in each case is inside the bar, 23 or 24.

As shown in Fig. 6, instead of two similar shoes slidably connected by the clamps, a one piece flat-sided sleeve, 26, may be employed which fits over adjoining end portions of pole lengths and within it is an oblong plate or shoe, 27, swiveled near top and bottom to the inner ends of crank screws, 28, which engage threaded openings in the adjacent wall of the sleeve and thus clamping pressure may be exerted on opposite sides of the inserted poles. The swiveled connections between the screws and the clamp plate, 27, prevent a separation and also provide means for the positive withdrawal of the clamp, 27. The swiveled connection is shown best in Fig. 7, being merely a collar on the screw on both sides of the plate, 27.

What I claim is:

1. A pole splice comprising in a permanently assembled unit oppositely acting members adapted to engage opposite sides of pole sections placed between them and separate actuating devices spaced apart vertically to cause relative movement of said members towards one another, said actuating devices being permanently associated with said members and a portion of the latter extending between and joining said devices.

2. A pole splice comprising in a permanently assembled unit oppositely acting members adapted to engage opposite sides of pole sections placed between them and separate actuating devices spaced apart vertically to cause relative movement of said members towards one another, said members being substantially similar shoes, said actuating devices being permanently associated with said members and a portion of the latter extending between and joining said devices.

3. A pole splice comprising opposite pole engaging shoes movable towards and from one another and a plurality of vertically

spaced apart clamps having cooperating members acting on the respective shoes, said clamps being permanently associated with said members and a portion of the latter extending between and joining said clamps.

5 4. A pole splice comprising opposite pole engaging shoes movable towards and from one another and a plurality of vertically spaced apart clamps having cooperating members acting on the respective shoes, consisting of a strap connected with one shoe having a threaded hole and a screw in said hole adapted to act against the other shoe.

10 5. A pole splice comprising opposite pole engaging shoes movable towards and from one another and means for causing movement towards one another comprising a strap passing about the two shoes horizontally and attached to one of the shoes, a plate attached to the other shoe having guide means for said strap and a clamp screw engaging a threaded hole in the strap and adapted to impinge against the outer side of said plate.

15 6. A pole splice comprising opposite pole engaging shoes movable towards and from one another and means for causing movement towards one another comprising a strap passing about the two shoes horizontally and attached to one of the shoes, a plate attached to the other shoe having guide means for said strap and a clamp screw engaging a threaded hole in the strap and adapted to impinge against the outer side of said plate, and means to secure the strap and plate to the 20 respective shoes comprising tongues on the shoes overlapping adjacent portions of strap and plate.

25 7. A pole splice comprising opposite pole engaging shoes, each consisting of a similar channel with side flanges of the two shoes opposite and adapted to overlap the same side of the spliced poles and means permanently holding them in such relative position, including screw means to move them with 30 clamp pressure upon opposite sides of aligning pole ends inserted between them.

40 In testimony whereof I hereunto affix my signature.

FRANK G. KINGSTON.
